(57) **CLAIM**

The ornamental design for a strain-relieving solar cell termination interconnect, as shown and described.

DESCRIPTION

FIG. 1 is a front, top, right side perspective view of the strain-relieving solar cell termination interconnect in accordance with the present invention;

FIG. 2 is a top view, the bottom view is a mirror image thereof;

FIG. 3 is a right side view thereof;

FIG. 4 is a left side view thereof;

FIG. 5 is a front view, the back view is a mirror image thereof;

FIG. 6 is a front view having segments 7A-7H delineated by dashed lines, the segments being illustrated in subsequent front views of FIGS. 7A-7H;

FIGS. 7A-7H are partial views of segments 7A-7H shown in FIG. 6, the segments being expanded seven times to illustrate the detail thereof;

FIG. 8 is a back view having segments 9A-9H delineated by dashed lines, the segments being illustrated in subsequent back views of FIGS. 9A-9H;

FIGS. 9A-9H are partial views of segments 9A-9H shown in FIG. 8, the segments being expanded seven times to illustrate the detail thereof;

FIG. 10 is a right side view having segments 11A-11E delineated by dashed lines, the segments being illustrated in subsequent right side views of FIGS. 11A-11E;

FIGS. 11A-11E are partial views of segments 11A-11E shown in FIG. 10, the segments being expanded seven times to illustrate the detail thereof;

FIG. 12 is a left side view having segments 13A-13E delineated by dashed lines, the segments being illustrated in subsequent left side views of FIGS. 13A-13E; and,

FIGS. 13A-13E are partial views of segments 13A-13E shown in FIG. 12, the segments being expanded seven times to illustrate the detail thereof.

(Continued)

The dashed and broken lines of FIGS. 6, 7A-7H, 8, 9A-9H, 10, 11A-11H, 12, and 13A-13H are for the purpose of illustrating design features and form no part of the claimed design.
